Primary Examiner — Freda S Nunn(74) *Attorney, Agent, or Firm* — Manatt, Phelps & Phillips, LLP(57) **CLAIM**

We claim the ornamental design for a case, as shown and described.

DESCRIPTION

FIG. 1 is a front perspective view of a case.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top end view thereof; and,

FIG. 8 is a bottom end view thereof.

The dash-dash broken lines indicate portions of the case that form no part of the claimed design. The pairs of closely adjacent, wavy, parallel, broken lines in the drawings indicate that any portion of the article beyond what is shown forms no part of the claimed design, and further the portions of the design that may be visible between the pairs of wavy lines have been removed for clarity.
